DESIGN FOR A CONSOLE CABINET FOR RADIO-PHONOGRAPH COMBINATION

Wallace Schier, Forest Hills, and David L. Doggett, Mount Kisco, N. Y., assignors to Federal Telephone and Radio Corporation, New York, N. Y., a corporation of Delaware

Application January 11, 1947, Serial No. 136,081

Term of patent 3½ years

(Cl. D56—4)

To all whom it may concern:

Be it known that we, Wallace Schier and David L. Doggett, citizens of the United States, residing at 150 Greenway Terrace, Forest Hills, Long Island, New York, and Millwood Road, Mount Kisco, New York, respectively, have invented a new, original and ornamental Design for a Console Cabinet for Radio-Phonograph Combination, of which the following is a specification, reference being had to the accompanying drawing, forming part thereof.

Figure 1 is a view in perspective of the console cabinet with the roll-back sections in the upper portion of the panel in closed position;

Figure 2 is a view in perspective taken at a different angle with the roll-back sections in open position exposing the radio dial and control knobs and with the lower portion of the front panel revolving 180 degrees about a vertical axis disclosing a record changer and shelf space for record albums; and

Figure 3 is a view in plan of the console cabinet shown in Figure 2.

The characteristic features of our design reside in the portions shown by means of full lines in the drawing.

We claim:

The ornamental design for a console cabinet for radio-phonograph combination, substantially as shown and described.

WALLACE SCHIER.
DAVID L. DOGGETT.
